Int. Cl. D22—05
U.S. Cl. D22—29

FIG. 1 is a top plan view of a fishing spoon showing my new design;

FIG. 2 is a plan view from a reverse position thereof;

FIG. 3 is a side elevational view;

FIG. 4 is a side elevational view from a reverse side thereof;

FIG. 5 is a front view thereof; and

FIG. 6 is a longitudinal cross section taken substantially on line 6—6 of FIG. 1, looking in the direction of the arrows.

The design is characterized by the gradual taper of its opposite ends, the upper and lower surfaces being outwardly curved and substantially flat, respectively, and by the enlarged section of said opposite ends relative to the general flatwise extent thereof.

This is a continuation-in-part of design application Ser. No. 24,952, filed Sept. 11, 1970, now abandoned.

I claim:

The ornamental design for a fishing spoon, substantially as shown and described.
